CLAIM

We claim the ornamental design for a narrow ink tank with serpentine air vents, as shown and described.

DESCRIPTION

FIG. 1 is a perspective view of the narrow ink tank with serpentine air vents showing the new design;
FIG. 2 is a front view thereof;
FIG. 3 is a rear view thereof;
FIG. 4 is a left side view thereof;
FIG. 5 is a right side view thereof;
FIG. 6 is a top plan view thereof; and,
FIG. 7 is a bottom plan view thereof.
The broken line showing of parts of the drawings is included for the purpose of illustrating use and environment and forms no part of the claimed design.
